UNITED STATES PATENT OFFICE

HARRY L. POHS, OF BROOKLYN, NEW YORK

PLAYING CARD

Application filed November 1, 1929. Serial No. 403,957.

This invention relates to improvements in the construction of cards and more particularly to cards such as are used in playing games.

5 The ordinary playing card, made of paper, is short lived, being easily soiled, subject to marking, swelling or thickening in use, due to absorbing moisture, and occasionally split along their edges and corners, rendering them no longer usable.

It is therefore an object of this invention to provide a card that is moisture proof, non-combustible and not susceptible of receiving finger prints, indentations, or other 15 marks of identification, such as are occasionally made by unscrupulous players.

A further feature is in the provision of a card having a desirable flexibility, finish and smoothness and which may be printed in 20 colors and fanciful designs as may be desired.

Another purpose is to produce a card which is substantially indestructible and which may be cleaned, should soiling occur, by usual methods.

25 These and other advantageous objects, such as moderate cost of manufacture and economy in use, are accomplished by the novel construction and combination of parts hereinafter described and illustrated in the accompanying drawing, constituting an important part of this disclosure, and in which:

Figure 1 is a plan view of the face of a playing card made in accordance with the invention, parts being broken away.

Figure 2 is a similar view of the back of the card.

Figure 3 is a greatly enlarged, fragmentary sectional view taken on line 3—3 of Figure 1.

40 What may be considered as the basis or foundation of the card is a strong woven textile fabric 5, preferably linen, impregnated and lined on both sides with phenolformaldehyde derivatives 6, such non-fibrous compositions, when subjected to the effect of heat

under pressure, presenting highly finished smooth surfaces, solid, opaque and of uniform thickness.

When the material has been finished, enclosing the fabric center, a second coat 7 is applied on the face and back to coalesce therewith, this encasing coating or laminæ being white so that the design can be imprinted and in any desired colors.

50 It is preferred that the printing be done with a chemical ink which will penetrate the outer coat and remain visibly permanent.

It will be understood that cards so constructed are unusually durable, their surfaces easily cleansed and that the material 60 is highly flexible, but not plastic, the cards being easily shuffled and dealt.

Obviously the material may be prepared in the form of a sheet of any area and the cards blanked therefrom in the same manner as if 65 the sheet was cardboard.

Although the foregoing is descriptive of the preferred embodiment of the invention, it will be apparent that minor changes may be made in its construction, without the exercise 70 of invention or conflicting with the scope of the claims hereto appended.

Having thus described the invention, what is claimed as new and desired to secure by Letters Patent, is:—

75 1. A new article of manufacture comprising a card having a woven textile center embedded in a phenolic composition, and covered on both sides with layers of similar material coalesced therewith and capable of receiving prints.

80 2. A new article of manufacture comprising a card having a woven textile center embedded in a phenolic composition, and coated with sheets of similar substance adapted to be 85 penetrated by chemical ink.

85 3. The process of making cards which consists in impregnating a woven textile fabric sheet with a phenolic condensate, coalescing 90 sheets of similar substance on both sides

thereof, cutting the sheet into desired size, and imprinting the cards with an ink adapted to penetrate the coalesced sheets.

4. As a new article of manufacture, a card comprising a woven textile center fabric, an opaque phenolic composition on both sides of said fabric to enter the interstices of said fabric, and a layer of white phenolic composition disposed over both sides of the opaque composition.

10 In testimony whereof I have hereunto affixed my signature.

HARRY L. POHS.
